NOAH S. HARTER, OF WAUKEGAN, ILLINOIS, ASSIGNOR TO CHAMPION FOLDING FURNITURE COMPANY, OF WAUKEGAN, ILLINOIS, A CORPORATION OF ILLINOIS

CAMPING COT

Application filed July 8, 1929. Serial No. 376,554.

This invention relates to portable folding cots, and particularly to certain details of construction. The cot comprises hollow steel side rails, each made in two sections connected by a joint which breaks upwardly in folding the cot. The side rails are preferably made of light steel tubing, rectangular in cross section, and on the adjacent ends of the sections of each rail sleeves are fitted, 10 each sleeve having side walls projecting beyond the end of the rail section to which it is attached, and these projecting walls having depending perforated ears which are connected together by a hinge pin. The 15 projecting side walls of one sleeve are adapted to enter the end of the opposing rail section and rest on the bottom thereof and the projecting side walls and top wall of the other sleeve are adapted to fit around the 20 sleeve of the opposing section when the cot is set up. Thus, parts of each section overlap parts on the other and prevent any tendency of the joint to sag or break downwardly when the cot is set up and in use. In the 25 type of cot to which my improvements are applied, the side rails have folding end pieces which incline upwardly when the cot is set up and a wire fabric is stretched between these end pieces. The tension of the fabric 30 and the weight of the human body upon it tend to force the rail sections toward one another, and in order to resist the end thrusts of the rail sections and prevent them from being forced endwise through the sleeves, I 35 provide tongues on the latter which engage the ends of the sections and form stops to prevent this relative movement. The tongues also serve to correctly position the sleeves in securing the latter to the rail sections. 40 The cot has legs composed of channel bar adopted to fold around the undersides of the rail sections. These legs are latched to the end pieces of the siderails when the cot 45 is set up, and the legs are prevented from spreading by links which are pivoted within the legs and are formed with long slots through which pins extend into the rail sections. The arrangement of the links is such 50 that when the legs are folded against the

rail sections the links automatically fold within the legs.

In the accompanying drawings,

Fig. 1 is a top plan view of the cot frame as it appears when set up;

Fig. 2 is a side elevation of the same with 55 the fabric attached;

Fig. 3 is a section through the central part of one of the side rails on the line 3—3 of Fig. 1;

Fig. 4 is a section on the line 4—4 of 60 Fig. 3;

Fig. 5 is a section on the line 5—5 of Fig. 3;

Fig. 6 is a section the same as that in 65 Fig. 3, but showing the parts of a side rail partly folded;

Fig. 7 is a section on the line 7—7 of Fig. 3; and,

Fig. 8 is a side elevation of one end of the 70 cot frame with the parts connected thereto partly folded.

Referring to Figs. 1 and 2 of the drawings, *a* and *a'* indicate the side rails of the cot frame, each composed of two sections 1 and 2, connected by a hinge joint *b*. The side rails have folding extension pieces 4 at their ends to which a wire fabric 5 is detachably connected when the cot is set up. The cot is supported by folding legs 6, and each leg 75 is braced by a link 7 and a latch 8, as herein-after more particularly described.

The sections 1 and 2 of the side rails are of equal length and composed of metal tubing which is rectangular in cross section, and these sections are connected by the joint *b*, which is adapted to break upwardly, in folding the cot, as illustrated in Fig. 6. The joint is composed of the parts *b'* and *b''* which are secured to the adjacent ends of the rail sections and are connected together by a hinge pin 9. The part *b'* comprises a split sleeve 10, rectangular in cross section, fitting closely around the rail section 1, the side walls 10^a of the sleeve projecting beyond the end 85 of the rail section and adapted to enter the section 2 when the cot is set up. As shown, these extended side walls of the sleeve 10 are bent inwardly, toward one another, along a diagonal line 10^b, and they are beveled from 90

top to bottom, as shown at 10°, so that the forward ends of the side walls may swing into and out of the end of the section 2 in setting up and folding the cot. Ears 10^a depend from the extended side walls 10^a and these ears are perforated to receive the hinge pin 9. The upper wall of the part 10^b also projects a short distance beyond the end of the section 1, and a tongue 10^c is pressed 5 downwardly from this wall into position to bear against the upper wall 1^a of the rail section. This tongue takes the endwise thrust which is applied to the part b' when the rail is straightened and the fabric is applied to the cot. The part b' may be secured against movement on the rail section 1 by spot welding.

The part b² of the hinge comprises a split sleeve 11 which fits closely around the rail section 2, and the sides 11^a and top 11^b of this part project beyond the rail section 2 so as to overlap the part or fitting b' on the section 1. The projecting sides and top of the part b² are expanded so that they will fit 20 easily around the top and sides of the part b' when the parts of the rail are in alinement as in Fig. 3. The top 11^b is cut away as shown at 11^c to permit the extended top of the part b' to fold without interfering with the top 25 11^b. The sides 11^a of the part b² have depending ears 11^d parallel with the ears 10^d of the part b' and the hinge pin 9 extends through the ears on both parts. A tongue 11^e is pressed downwardly from the top wall 30 of the part b² and engages the end of the rail section 2, to take the end thrust which is applied to the part b² when the cot is set up. The part b² may also be spot welded to the rail section 2, if desired.

40 When the sections of the side rails are brought into alinement, as in Fig. 3, it will be noted that the extended ends of the hinge part b', on the rail section 1, lie within and rest upon the bottom wall of the rail section 2 and that the extended top portion 11^b of the part b² on the rail section 2 rests upon the top wall 1^a of the rail section 1. This double overlapping of the parts strengthens the joint against any tendency 45 to sag downwardly and the sleeves strengthen the rail sections at their adjacent ends.

The extensions 4 of the side rails are of 50 channeled steel, pivoted to the ends of the rails and adapted to fold over and around the upper sides of the rails. The latches 8, pivoted to these extensions, are adapted to engage pins 13 on the legs, and the links 7, pivoted to the legs, engage pins 14 on the side rails. The links prevent spreading of 55 the legs and the latches hold the end extensions of the side rails down against the tension of the wire fabric 5 which tends to pull the end extensions upwardly. The legs 6 are of channeled steel and each link 7 has 60 one end pivoted at 15 within a leg and it

also has a longitudinal slot 7^a through which the pin 14 on the side rail extends. The side rails at the opposite sides of the cot are connected together by folding toggle 70 braces 16.

The legs fold around the undersides of the rail sections, and, as will be evident from an inspection of Fig. 8, in folding the legs the links automatically fold within them. It is unnecessary to touch the links either 75 in folding or unfolding the cot frame.

What I claim is:

A side rail for a folding cot frame, composed of two sections of angular metal tubing and an upwardly breaking joint connecting said sections, said joint comprising sheet metal sleeves fitting around the adjacent ends of the sections, one sleeve having side and top walls extending beyond the section to which it is attached and adapted to fit around the sides and top of the sleeve on the opposing section, and the latter sleeve having projecting side walls adapted to enter the opposing section and rest on the bottom wall thereof, when the cot is set up, the extended side walls of both sections having depending ears and a hinge pin extending through said ears.

In testimony whereof I affix my signature.

NOAH S. HARTER.
